UNITED STATES PATENT OFFICE.

GERARD BEEKMAN, OF NEW YORK, N. Y.

PROPELLING AND BRAKING MECHANISM.

SPECIFICATION forming part of Letters Patent No. 638,693, dated December 12, 1899.

Application filed December 28, 1898. Serial No. 700,506. (No model.)

To all whom it may concern:

Be it known that I, GERARD BEEKMAN, a citizen of the United States, residing at New York, in the county and State of New York, 5 have invented certain new and useful Improvements in Propelling and Braking Mechanism for Cycles, of which the following is a specification.

My invention relates to certain structural 10 improvements in bicycle-propelling mechanism analogous in principle to that shown and described in Letters Patent No. 592,230, granted to me October 26, 1897.

In my aforesaid patent I have described 15 mechanism provided with pedals separately connected through the medium of clutch mechanism to the tubular driving-shaft, so as to drive the shaft forward by the depression of the alternately-descending pedals through 20 the automatic action of the clutch mechanism or to provide means for pedal-braking by foot-pressure applied to both pedals or when the pedals are held to automatically release the rotary hollow shaft for coasting.

25 My present invention provides these facilities under an improved and simplified construction.

Referring to the accompanying drawings, which form a part of this specification, Figure 1 represents a cross-section through the 30 frame of a bicycle, showing the internal construction of the shaft-hanger and the tubular driven shaft and driving-crank hubs mounted therein. Fig. 2 is a transverse section of the same on line 2 2, Fig. 1. Figs. 3 and 4 are detail views of the automatic clutch-operating mechanism, Fig. 3 being a face view and Fig. 4 a side view thereof. Fig. 5 is a view 35 similar to Fig. 1, showing a modification.

40 Referring to Figs. 1 to 4, A represents the crank-hanger, which is rigidly mounted in the frame of a bicycle in the customary manner.

B represents the rotary driven element or 45 hollow shaft, mounted in the said hanger through the medium of ball-bearings b in customary manner.

B' is the sprocket-wheel, mounted on the tubular shaft B.

50 C C' represent the pedal-cranks, oppositely disposed, as usual, on the axis of rotation and having hubs c c', respectively, extending within the driven hollow shaft B, the said

hub members and the surrounding interior surface of the hollow shaft B in which they are contained being of frusto-conical form, 55 as clearly shown in Fig. 1, so that when the hub members are forced together toward the center they will tend to grip the conical interior surface of the hollow shaft and when forced outward will release the same, so as 60 to permit free relative rotation between the crank-hubs and between the respective crank-hubs and the hollow shaft. Inserted in the longitudinal angular recess in the conical surface of each of the hub members c c' is a friction-clutch roller v, which in the forward rotation of the respective cranks for propelling purposes is forced outwardly against the surrounding interior surface of the hollow shaft B, so as to produce effective driving friction 65 between the opposed surfaces of the hub members c c' and the said hollow shaft. The hub member c is constructed with a longitudinal prolongation c² concentric with the axis, extending within the hub member c', so as to 70 confine the said hub members to relative concentric movement. The hub members are, furthermore, tied together by a central bolt G, formed with a head g to confine the hub member c' and its crank-arm C', the said bolt G being 75 screwed permanently into the hub member c, as shown at g', and clamped in the desired adjusted position by a clamp-nut g², which engages the threaded reduced end of bolt G and seats in a shoulder in the hub c. A spiral or 80 cup spring F, surrounding the reduced portion c² of the clutch member c, bears outwardly against the opposed shoulders of the said clutch members, as shown in Fig. 1, so as to 85 tend to force them apart.

Upon the extremity of the extension c² of the clutch member c is mounted a clutch-disk p, formed on its inner face with angular or inclined recesses, as represented in Fig. 4, and a corresponding recessed disk q is mounted 95 in the hub member c' of the crank C'. Within the cavities formed by the recesses p' q' of the respective clutch-disks p q are frusto-conical rollers r. To permit the relative adjustment of the recessed clutch-disks p q, the 100 clutch-disk p, which is confined by the head g of the central bolt G, is fitted to slide by a tongue - and - groove connection T upon extremity c² of the hub member c, so that by

turning the bolt G in the hub member c the clutch-disks p q may be set closer together upon the interposed conical clutch-rollers r.

From the above construction it will be apparent that any flexure or relative angular movement between the cranks C and C' causes the inclined surfaces of the clutch-disks p q to bear on the interposed frusto-conical rollers r to force the hub members c c' together longitudinally (against the tendency of spring F) with wedge-like action between their conical surfaces and the internal conical surfaces of the tubular shaft B, and hence the simultaneous downward pressure of the feet on both pedals will produce a braking effect upon the tubular shaft. If the crank-arms are held by the feet with equal pressure, not sufficient to compress spring F and flex the crank-arms on their axis of rotation, the hub members are automatically held outwardly by the interposed helical spring F releasing the tubular driving-shaft B and allowing the wheel to run free, as in coasting. A successive downward pressure of the feet on the cranks in the pedaling action locks the hub to the hollow shaft through clutch-rollers v, so as to produce the desired propelling action. The interposed spring F should be so constructed as to compress or expand along the axis of the pedal-shafts stiffly, but turn readily around said axis, thus allowing the omission of the antifriction-bearings shown in my prior patents.

In Fig. 5 I have shown a slight modification. The extension c² of hub member c is omitted, and the tie-bolt G, of larger diameter than in Fig. 1, passes through hub members c c' and is splined into the hub member c at g³, so as to move positively with it in a rotary direction. The hub member c' is formed with an internal longitudinal groove c³ to allow the spline g³ to pass through when the parts are assembled, the tie-bolt G being then turned one-half a revolution in the hub member c' to bring the spline into position to engage the spline-groove in the hub member c. The tie-bolt is confined by the nut N and clamp-nut N' engaging it and a shoulder in the hub member c. The clutch members p q are respectively formed integral with the bolt-head g and hub member c', and the clutch-rollers r, described in connection with Fig. 1, are inserted between members p q. The operation of this form of the device is practically the same as the form shown in Fig. 1.

Having thus described my invention, what I claim as new therein, and desire to secure by Letters Patent, is—

1. The combination of the hollow driven shaft B, converging in internal diameter from each end toward the center, the oppositely-

disposed pedals C, C' having frusto-conical hub members c, c' extending within the hollow shaft and capable of limited relative longitudinal and rotary movement, the recessed clutch members p, q secured respectively to the hub members c, c', the clutch-rollers r, interposed between clutch members p, q, and the tie-bolt G, substantially as and for the purpose set forth.

2. The combination of the hollow shaft B converging in internal diameter from each end toward the center, the frusto-conical hub members c, c' having relative longitudinal movement within the hollow shaft and capable of limited relative rotary movement, said hub member c having a projection c² extending concentrically within the member c', the recessed clutch-disk p mounted on the extremity of the hub projection c², the opposed recessed clutch-disk q, mounted in the hub member c', the rollers r interposed between the recessed faces of the disks p, q, and the tie-bolt G, whereby relative rotary movement of the hub members forces them together within the surrounding conically-formed hollow shaft B, as explained.

3. The combination of the hollow shaft B converging in internal diameter from each end toward the center, the frusto-conical hub members c, c' the member c having an extension c² within the member c', the recessed clutch-disk p mounted adjustably on the extremity of the extension c², the bolt G confining the clutch-disk p adjustably on the end of the hub extension c², the recessed clutch-disk q mounted in the recess in the hub member c', and the interposed clutch-rollers r, substantially as and for the purpose set forth.

4. The combination of the hollow shaft B converging in internal diameter from each end toward the center, the hub members c, c' having relative longitudinal movement and limited relative rotary movement, the automatic clutch mechanism p, q, r by which they are moved relatively endwise by their relative rotary movement, the tie-bolt G, and an interposed spring F tending to force them longitudinally outward, as and for the purpose explained.

5. The combination of the hollow shaft B converging in internal diameter from each end toward the center, the hub members c, c', the clutch mechanism p, q, r tending to force them longitudinally inward by their relative rotary movement, the clutch-rollers v mounted in angular recesses in the peripheries of the hub members c, c' respectively, and the tie-bolt G, as and for the purpose set forth.

GERARD BEEKMAN.
